UNITED STATES PATENT OFFICE

141,798

DESIGN FOR A WEIGHING SCALE

Henry Dreyfuss, New York, N. Y., assignor to Fairbanks, Morse & Co., Chicago, Ill., a corporation of Illinois

Application March 26, 1945, Serial No. 118,719

Term of patent 14 years

(Cl. D52—10)

To all whom it may concern:

Be it known that I, Henry Dreyfuss, a citizen of the United States, residing in the city of New York, county of New York, State of New York, have invented a new, original, and ornamental Design for a Weighing Scale, of which the following is a specification, reference being had to the accompanying drawing, forming a part thereof.

In the drawing:

Fig. 1 is a perspective view of a weighing scale, showing my new design, and

Fig. 2 is a top plan view thereof.

The back of the scale (not shown) is plain.

I claim:

The ornamental design for a weighing scale, substantially as shown and described.

HENRY DREYFUSS.
